UNITED STATES PATENT OFFICE.

ROY R. MELTON, OF CAMDEN, TENNESSEE.

AUTOMOBILE NUMBER-PLATE.

1,397,136.

Specification of Letters Patent. Patented Nov. 15, 1921.

Application filed August 31, 1920. Serial No. 407,262.

To all whom it may concern:

Be it known that I, Roy R. MELTON, a citizen of the United States of America, and resident of Camden, in the county of Benton 5 and State of Tennessee, have invented certain new and useful Improvements in Automobile Number-Plates, of which the following is a specification.

This invention relates to automobile license tags and particularly to a device having novel means whereby a body or main element or plate is provided, the said invention having for its object the provision of a plate or tag resulting in great economy 10 for renewals or subsequent years in the main body of the plate is permanent, the said plate being provided with removable parts indicating the change in the year so that the only necessity for renewing the 15 license is to secure a new year plate, a part of the device which is relatively small and comparatively inexpensive, so that is not necessary to discard the whole plate each year, but it is only necessary to discard 20 a small part thereof bearing the year date or number.

A still further object of this invention is to produce a plate of the character indicated, having novel means for removably 25 securing the supplemental plate therein so that it can be easily applied or removed.

With the foregoing and other objects in view, the invention consists in the details of construction and in the arrangement and 30 combination of parts to be hereinafter more fully set forth and claimed.

In describing the invention in detail, reference will be had to the accompanying drawings forming part of this specification 35 wherein like characters denote corresponding parts in the several views, and in which—

Figure 1 is a view in perspective of a license plate embodying the invention,

Fig. 2 a sectional view on the line 2—2 of Fig. 1,

Fig. 3 a sectional view on the line 3—3 of Fig. 1,

Fig. 4 a plan view of the plate on a reduced scale, and

Fig. 5 a plan view of the removable tag on the same scale.

In these drawings 10 denotes the number plate which may have suitable indicia there-

on, such as the state of origin and the number, the said plate having an offset portion 11 formed by extending a portion of the body of the plate rearwardly and then reducing its length by the production of the loops 12 and 13 which form guides in which the 55 year tag 14 is slidable, the said year tag having its upper end 15 doubled back to embrace the plate, and the said tag and plate have coinciding apertures 16 and 17 to receive fastenings by which the plate can be 60 secured to a bracket of the lamp.

The plate furthermore has a depending ear 18 which is bent upwardly in front of the recess of the plate to form a guide for the lower end of the tag, as fully shown in 70 Fig. 2.

It will be seen that a plate made in accordance with this invention will result in a saving in the second year of the whole plate, as well as its numbering, and that 75 only the year tag need to be renewed, and as the year tag is a comparatively small part of the structure the saving will be comparatively great.

I claim:

1. In an automobile number plate, a body having a portion throughout the vertical dimensions of the plate proper extending rearwardly, the edges of the rearwardly extending portion being doubled on the plate 85 and spaced from the plate to form guide-ways, an integral ear on the lower edge of the rearwardly extending portion, the said ear being shaped to embrace the lower ends of the guide-ways and extending upwardly 90 to guard the lower ends of the said guide-ways, and a year plate slidable in the said guide-ways having its lower end embraced by the said ear.

2. In an automobile number plate, a body 95 having a portion throughout the vertical dimensions of the plate proper extending rearwardly, the edges of the rearwardly extending portion being doubled on the plate and spaced from the plate to form guide-ways, an integral ear on the lower edge of the rearwardly extending portion, the said ear being shaped to embrace the lower ends of the guide-ways and extending upwardly 100 to guard the lower ends of the said guide-ways, a year plate slidable in the guide-ways and having its lower end embraced by the ear, and a rearwardly extending upper

end on said year plate embracing the upper edge of the rearwardly extending portion of the said plate.

3. In an automobile number plate, a body having a portion throughout the vertical dimensions of the plate proper extending rearwardly, the edges of the rearwardly extending portion being doubled on the plate and spaced from the plate to form guide-
ways, an integral ear on the lower edge of the rearwardly extending portion, the said ear being shaped to embrace the lower ends

of the guide-ways and extending upwardly to guard the lower ends of the said guide-ways, a year plate slidable in the said guide-ways having its lower end embraced by the ear, a rearwardly extending upper end on said year plate embracing the upper edge of the rearwardly extending portion of the said plate, and an element extending through the plate and the year plate for preventing vertical movement of the year plate. 15 20

ROY R. MELTON.
